UNITED STATES PATENT OFFICE.

AUGUST MANTEUFEL, OF CHICAGO, ILLINOIS.

LOCK.

Application filed February 1, 1923. Serial No. 616,265.

To all whom it may concern:

Be it known that I, AUGUST MANTEUFEL, a citizen of the United States, and a resident of the city of Chicago, county of Cook, 5 and State of Illinois, have invented certain new and useful Improvements in Locks, of which the following is a specification.

My invention relates to improvements in locks, and has for its principal object the 10 provision of an improved construction of this character which will be highly efficient in use and economical in manufacture.

Among other objects of the invention is the provision of certain elements which will 15 greatly facilitate the manufacturing of the invention and the assembling of the same.

Other objects will appear hereinafter.

The invention consists in the combinations and arrangements of parts hereinafter described and claimed.

The invention will be best understood by reference to the accompanying drawings forming a part of this specification, and in which,

25 Fig. 1, is a side elevational view of a lock embodying the invention;

Fig. 2, is an end elevational view of the same;

Fig. 3, is a view taken substantially on 30 line 3—3 of Fig. 1;

Fig. 4, is a plan view of the revolvable barrel cap embodied in the invention;

Fig. 5, is a sectional view of the invention taken substantially on line 5—5 of Fig. 35 6;

Fig. 6, is a side elevational view of the revolvable barrel or tumbler holder embodied in the invention;

Fig. 7, is a plan view of one of the tumblers embodied in the invention;

Fig. 8, is a longitudinal sectional view of the invention;

Fig. 9, is a side elevational view of the revolvable barrel or tumbler holder showing 45 the unfinished tumblers projecting therefrom;

Fig. 10, is a longitudinal sectional view of the invention similar to that illustrated in Fig. 8;

50 Fig. 11, is a sectional view of the same taken substantially on line 11—11 of Fig. 10; and

Fig. 12, is an enlarged sectional view of the same taken substantially on line 12—12 55 of Fig. 10.

Referring to the drawings 20 indicates a

lock barrel having oppositely arranged slots 21 formed therein for the reception of the outer extremities of the tumblers of the lock to prevent the tumbler holder 22 from revolving. The tumbler holder 22 is provided with an enlarged head 23 adapted to seat within an annular recess 24 formed in the lock barrel 20.

The construction so far described is embodied in approved locks of the character herein set forth and reference to such parts are only made for the purpose of bringing out the legitimate combination of the present invention.

The tumbler holder 22, as shown in Fig. 5, is provided with longitudinally extending slots 25 and leg portions 26 arranged at one end thereof, the latter being formed at an angle of approximately forty-five degrees with respect to each other. The cap 28, Fig. 4, of the tumbler holder is provided with notches 29 for the reception of the leg portions 26. The lock tongue 30 is formed integral on a disc 31 having openings 32 cut therethrough, through which reduced portions 34' of the legs 26 project. The disc 31 is mounted over the cap 28 and when in such position the projecting portions 34' are riveted over, securing the disc in such position. The lock tongue is adapted to function with a cooperating lock member (not shown) of any approved construction. Formed in the cap 28 and the opposite end of the tumbler holder 24 are registering key 90 slots 33 and 33' through which the key 34 is inserted.

The tumblers 35, illustrated in Fig. 7, are formed with slots 36 for the passage of the key 34 and are mounted in the tumbler holder 22 with their opposite extremities 95 projecting through the opposite slots 25.

In manufacturing the lock, the tumblers 35 are arranged in pile form with their extremities projecting beyond the periphery of the tumbler holder, Fig. 9, and with their key slots 36 registering with one another. The key 34 is used as a pattern for cutting the tumblers so as to function only with that particular key. This is accomplished by inserting the key within the tumbler holder and cutting the extremities of the tumblers flush with the periphery of the tumbler holder with the key inserted therein. Due to the irregular side edges of the key 105 the tumblers when the key is withdrawn from the tumbler holder will be irregularly

distorted and may be thrown into the slots 21 of the lock barrel. When the key is again inserted within the tumbler holder the extremities of the tumblers are drawn again 5 flush with the periphery of the tumbler holder. It is one of the objects of the invention to provide means for positively distorting the tumblers upon withdrawal of the key. I accomplish this object by the use of 10 a spring member 37 which passes through openings 38 formed in triangularly shaped projecting portions 39 formed integral with the tumblers. One end of the spring member rests upon the inner surface of the head 15 23, Fig. 8, and the other end passes into a hollow portion 40 formed in the cap 28, Fig. 4. When the cap 28 is mounted in its respective position, as best illustrated in Fig. 8, the spring 37 is compressed and 20 irregularly throws the ends of the tumblers into the opposite slots 21. The tumblers in this position prevent the tumbler holder from revolving and hold the tumbler holder in such position until the key, used as a pattern for cutting the ends of the tumblers is 25 inserted within the tumbler holder. When the key is inserted within the tumbler holder the tumblers are drawn in such manner that the opposite ends are again flush with the 30 outer periphery of the tumbler holder and being in such position the tumbler holder is permitted to turn.

This provision of the spring member not only throws the tumblers in the manner 35 stated but also greatly facilitates the mounting of the tumblers within the tumbler holder for the reason that the spring member will hold the tumblers therein during the assembling of the various parts of the 40 tumbler holder.

A further object is the provision of a key 45 guide which will facilitate insertion of the key through the key slots, holding the key against lateral movement. This object is accomplished by forming a small protuberance 41 on the inner wall of the tumbler holder and forming a recess 42 in such protuberance into which the rib 43 of the key works when the key is inserted through the 50 key slots. By this provision of the key guide 41 the key when inserted within the tumbler holder will always take the same position as at the time when it was used as a pattern for cutting the tumblers.

In the present constructions of locks of 55 the character herein described, and where tumblers similar to those illustrated in the drawings are used there is no provision for distorting the tumblers after withdrawal of 60 the key and I have found by experience that by the provision of the spring member, the tumblers will not stick in the tumbler holder but will be forced into the grooves of the lock barrel, by the spring member, upon 65 withdrawal of the key.

Oftentimes in manufacturing locks of the character herein described, through carelessness or through the use of improper tools, the key slots are often made too large and the key when inserted within the tumbler 70 holder, having excess room will not properly distort the tumblers in the required manner. This action of the key will necessarily cause a great deal of trouble, and possibly prevent the drawing of the tumblers from the 75 slots. I alleviate this difficulty by the employment of the key guide the value of which is manifest.

It is apparent from the description herein 80 that my improved lock has many advantages over the present locks on the market and one which will be highly efficient in use, designed so as to be adapted for locking purposes of any sort.

While I have illustrated and described the 85 preferred form of construction for carrying my invention into effect, this is capable of variation and modification without departing from the spirit of the invention. I, therefore, do not wish to be limited to the 90 precise details of construction set forth, but desire to avail myself of such variations and modifications as come within the scope of the appended claims.

Having described my invention, what I 95 claim as new and desire to secure by Letters Patent is:

1. A lock including a holder having oppositely arranged slots formed therein, tumblers arranged in said holder in pile form and having integral triangular projections with registerable openings therein, a spring passing through said openings for irregularly distorting said tumblers, and a key for operating said tumblers.

2. A lock including a holder having oppositely arranged slots formed therein, tumblers arranged in said holder in pile form and having registerable openings therethrough, a spring passing through said openings, a cap for said holder having a portion for the reception of one end of said spring, said cap being adapted to compress said spring for irregularly distorting said tumblers, and a key for operating said tumblers.

3. A lock including a holder having leg portions formed at one end, a cap having means for receiving said leg portions to fasten said cap thereto, tumblers having registerable openings therein, and a member passing through said openings and engaging said cap for irregularly distorting said tumblers.

4. A lock including a holder having leg portions formed at one end, a cap having slots for the passage of said leg portions and provided with a hollowed out portion, tumblers having integral triangularly shaped portions arranged in pile form within said

holder and having registering openings formed in said triangularly shaped portions, and a spring member passing through said openings and into said hollowed out portion for irregularly distorting said tumblers.

5. A lock including a tumbler holder having oppositely arranged slots formed therein and leg portions formed at one end thereof, a cap having notches for the reception of 10 said leg portions and provided with a hollowed out portion, tumblers arranged in said holder having their extremities projecting into said slots, a member passing through said tumblers and extending into said hollowed out portion for irregularly distorting 15 said tumblers, and a member insertable within said holder for drawing said tumblers in a position flush with the periphery of said holder.

20. 6. A lock including a holder having oppositely arranged slots formed therein, tumblers arranged in said holder in pile form and having integral triangularly shaped projections, a member passing through said triangularly shaped projections, a cap for said holder having a hollowed out portion for the reception of one end of said member, said cap being adapted to compress said member when mounted in position causing said member to 25 irregularly distort said tumblers, and a member insertable within said holder for drawing said tumblers in such position that the extremities thereof will be flush with the periphery of said holder.

30. 7. A lock including a holder having oppositely arranged slots formed therein, tumblers arranged in said holder in pile form and having integral triangularly shaped projections, a member passing through said triangularly shaped projections, a cap for said holder having a hollowed out portion for the reception of one end of said member, said cap being adapted to compress said member when mounted in position causing 35 said member to irregularly distort said tumblers, a member insertable within said holder for drawing said tumblers in such position that the extremities thereof will be flush with the periphery of said holder, and means for guiding said last named member.

50. 8. A lock including a holder having oppositely arranged slots formed therein, a barrel for said holder having oppositely arranged slots formed therein, tumblers ar-

ranged in pile form within said holder and 55 having their extremities projecting into the slots thereof, a member for distorting said tumblers forcing the extremities thereof into the slots of said barrel, means adapted to be inserted within said holder for drawing the 60 extremities of the tumblers from the slots in said barrel, and guide means to prevent incorrect insertion of said member.

9. A lock including a holder, a barrel for 65 said holder having oppositely arranged slots formed therein, tumblers arranged in pile form in said holder and having their extremities projecting into said slots to prevent movement of said holder, a member with means arranged longitudinally of its 70 side adapted to be inserted within said holder for drawing the extremities of said tumblers out of said slots, means for receiving said side means and guiding said last named member, and means for distorting 75 said tumblers causing the extremities of said tumblers to pass into said slots again upon withdrawal of said member.

10. A lock including a barrel, a holder mounted for movement within said barrel, 80 members arranged in said holder for locking said holder against movement, a key with means on its side insertable within said holder to permit movement thereof, a protuberance formed on the inner wall of said 85 holder and having a recess formed therein for the reception of said last named means adapted to guide said key upon being inserted within said holder.

11. A lock comprising in combination with 90 a revolvable barrel having a key slot formed therein, a key having a rib formed thereon adapted to be inserted within said barrel through said key slot, and means for guiding said key, said means comprising a recess 95 for the reception of the rib of said key.

12. A lock comprising in combination with a revolvable barrel having a key slot formed therein and a key having a rib insertable within said barrel through said key slot, a 100 protuberance formed on said barrel and having a recess formed therein for the reception of the rib of said key adapted to guide said key upon being inserted within said barrel.

In testimony whereof I have signed my 105 name to this specification.

AUGUST MANTEUFEL.
